UNITED STATES PATENT OFFICE.

WILLIAM C. YATES, OF SCHENECTADY, NEW YORK, ASSIGNOR TO GENERAL ELECTRIC COMPANY, A CORPORATION OF NEW YORK.

AUTOMATIC MOTOR-STARTER.

No. 910,762.

Specification of Letters Patent.

Patented Jan. 26, 1909.

Application filed May 9, 1908. Serial No. 431,935.

To all whom it may concern:

Be it known that I, WILLIAM C. YATES, a citizen of the United States, residing at Schenectady, county of Schenectady, State 5 of New York, have invented certain new and useful Improvements in Automatic Motor-Starters, of which the following is a specification.

This invention relates to means for controlling electric motor circuits and has for its object the provision of a device whereby an electric motor may be started and brought up to running speed in a reliable, safe and efficient manner.

15 My invention relates more specifically to the starting of alternating current motors of the type which are controlled by connecting them to a source of low voltage for starting and then increasing the impressed voltage for running.

20 One of the objects of my invention therefore is to provide a simple and efficient automatic starter for alternating current circuits by means of which motors may be controlled from a distance either manually or by automatic switching devices such as pressure governors, float switches, and the like.

In the application filed by Charles D. Knight, Serial No. 289,774, there is disclosed a starting mechanism of the type above described for starting a three phase motor. In the starting of two phase motors, however, with a device such as is described in said application, it has been observed 35 that if one phase of the transmission line is grounded or is short-circuited, the motor will run single phase thus overheating and burning out the motor.

One of the objects of my invention therefore is to protect a device of this sort when used on two phase circuits. This I accomplish by having the no-voltage magnet, which holds the mechanism in running position, controlled by both phases of the circuit 45 so that in case of failure of either phase, the no-voltage magnet will be deenergized causing the parts to return to starting position.

In the accompanying drawing I have shown my invention embodied in concrete 50 form.

The type of starting mechanism employed is that disclosed in the application above referred to and will, therefore, be described only in a general way.

55 A is an induction motor of the squirrel-

cage type; B is the compensator or auto-transformer; C is the starting switch; D is the running switch; and E is the master controller. The starting switch C is arranged to connect the motor A to the two phase 60 mains through the transformer B while running switch D connects the motor directly to the line. When the switch 10 is closed the no-voltage magnet 11 is energized as is also the starting switch C, the locking magnet 12 and the solenoid 13 of the master controller E. These circuits are closed by an electromagnetic switch 14 which is energized by phase $a a'$ of the circuit while the energizing circuit is tapped off of the phase $b b'$. 65 When therefore the switch 10, which may be operated manually or otherwise, is closed the switch C is operated, connecting the two phase mains $a a'$ and $b b'$ to the transformer B through the three bridging contacts 15, 70 16, and 17, and at the same time connecting the motor A to the transformer through the bridging contacts 18, 19 and 20. When the switches are closed by the solenoid of the switch C, the solenoid is deenergized by the 75 lifting of the switch lever 21 pivoted at 22, but the core is held in its raised position by means of the latch 23 which is moved into a slot 24 in the core by means of the locking magnet 12. In the meantime the solenoid 80 13 of the master controller, which has been energized, has caused its core 25 to travel upwards against the retardation of the dashpot 26 until the bridging contact 27 opens the circuit of the locking magnet 12 and at the 85 same time closes the circuit of the solenoid switch D. This causes the starting switch E to be opened, cutting off the transformer from the line and from the motor, and at the 90 same time switch D closes the circuit through the motor at the contacts 28 and 29. These contacts are held up by means of the no-voltage magnet 11 which is controlled from both phases of the circuit. If now one of the 95 phases, as for instance $a a'$, is short-circuited, the magnet 14 would be deenergized as would magnet 11 whereupon all of the parts 100 would return to starting position. The same would be true if the phase $b b'$ should be short-circuited. In this manner I have protected the device against danger from the 105 grounding of either phase, and while I have described my invention in connection with a specific type of mechanism arranged to operate in a specific way, it should be understood 110

that I do not wish to limit my invention thereto except in so far as it is limited by the scope of the claims annexed hereto.

What I claim as new and desire to secure 5 by Letters Patent of the United States, is,

1. The combination with an alternating current motor and a polyphase supply circuit of a transformer, a plurality of automatically-operated switches, for first connecting 10 the motor to the supply circuit through the transformer and then connecting the motor directly to the supply circuit, and a no-voltage magnet responsive to any phase of the circuit.
- 15 2. The combination with an alternating current motor and a two phase supply circuit, of a voltage controlling device, two switches arranged to connect said motor in different relations to said controlling device 20 for starting and for running, and a no-voltage magnet for the running switch controlled by both phases of the circuit.
- 25 3. The combination with an alternating current motor and a two phase supply circuit, of a voltage controlling device, a plurality of automatically operated switches for first connecting the motor to the supply circuit through the controlling device and then connecting the motor directly to the supply 30 circuit, and a no-voltage magnet energized by one phase and having its energizing circuit controlled by the other phase.
- 35 4. The combination with an alternating current motor and a two phase supply circuit, of a voltage controlling device, a plurality of automatically operated switches for first connecting the motor to the supply circuit through the controlling device and then connecting the motor directly to the supply 40 circuit, a no-voltage magnet energized by one phase, and an electromagnetic switch in the energizing circuit of said magnet controlled by the other phase.
- 45 5. The combination with an alternating current motor and a two phase supply circuit,

circuit, of a voltage controlling device, two switches arranged to connect said motor in different relations to said device for starting and for running, a control system for said switches comprising means automatically 50 operating to close the starting switch and then close the running switch and open the starting switch after a predetermined interval, and a no-voltage magnet for the running switch controlled by both phases of the 55 circuit.

6. The combination with an alternating current motor and a two phase supply circuit, of a voltage controlling device, two switches arranged to connect said motor in 60 different relations to said device for starting and for running, a control system for said switches comprising means automatically operating to close the starting switch and then close the running switch and open the 65 starting switch after a predetermined interval, and a no-voltage magnet for the running switch energized by one phase and having its energizing circuit controlled by the other phase.

7. The combination with an alternating current motor and a two phase supply circuit, of a voltage controlling device, two switches arranged to connect said motor in different relations to said device for starting 75 and for running, a control system for said switches comprising means automatically operating to close the starting switch and then close the running switch and open the starting switch after a predetermined interval, a 80 no-voltage magnet for the running switch energized by one phase, and an electromagnetic switch in the energizing circuit of said magnet controlled by the other phase.

In witness whereof I have hereunto set my 85 hand this 8th day of May, 1908.

WILLIAM C. YATES.
